AIR SEAL FOR BOILER DRUMS

Max H. Kuhner, Cornwells Heights, Pa., assignor,
by mesne assignments, to Riley Stoker Corporation,
Worcester, Mass., a corporation of
Massachusetts

Application October 15, 1931. Serial No. 569,017

4 Claims. (Cl. 110—1)

This invention relates to air seals for boiler drums, and more particularly to a construction arranged to prevent leakage of air into the furnace around the drums of water tube boilers.

One form of water tube boiler comprises a plurality of drums or shells connected by banks of water tubes. One or more of the drums is usually anchored to the supporting frame work, while the other drums are free to move and thus allow the tubes to expand or contract as the temperature varies. When the ends of a drum extend outside the walls of the furnace, it is necessary to provide a clearance space between the drum and the furnace wall, so that this movement of the drum may take place. Since the interior of the furnace chamber is ordinarily at a pressure slightly below that of the atmosphere, there is a decided tendency for air to leak into the furnace through the clearance space. Any such leakage reduces the efficiency of the boiler and furnace, and is highly undesirable.

It is accordingly the main object of my invention to provide a simple and effective construction which will prevent leakage of air into a furnace between a boiler drum and the furnace wall through which it extends.

It is a further object of the invention to provide an air seal which will allow the boiler drum to move freely relative to the furnace wall, and which will at all times prevent air leakage between these parts.

It is a further object of the invention to provide an air seal which will remain tight regardless of the longitudinal expansion of the drum itself.

It is a further object to provide an air seal which is simple and inexpensive to manufacture and install.

It is a further object to provide a simple and effective means for holding heat insulating material in place on the ends of the drum.

With these and other objects in view, as will be apparent to those skilled in the art, my invention resides in the combination of parts set forth in the specification and covered by the claims appended hereto.

In accordance with my invention I provide a furnace wall having an opening therein, and a boiler drum mounted within the furnace with one end projecting through the opening in the wall. A sealing ring surrounds the drum, and this ring is preferably held in sliding contact with the wall by a suitable means, such as a series of clamps mounted on the outside of the

wall. The inner diameter of the ring is preferably slightly greater than the outer diameter of the drum, so that the drum may expand freely lengthwise without moving the ring, and air leakage between these parts may be prevented by flexible packing. This packing may be held in place by a sleeve formed integral with the sealing ring. Heat insulating material is preferably provided on the end of the drum, and this material may be held in place by wires. The ends of the wires may be connected to the sealing ring.

Referring to the drawing illustrating one embodiment of the invention, and in which like reference numerals indicate like parts,

Fig. 1 is an elevation showing a portion of the outside of a furnace wall having a boiler drum extending therethrough;

Fig. 2 is an enlarged section on the line 2—2 of Fig. 1;

Fig. 3 is a perspective view of a clamp; and

Fig. 4 is a perspective view of a sealing ring sector.

The embodiment illustrated in the drawing comprises a vertical furnace wall 10 constructed of suitable refractory and heat insulating material, and protected on the outside by a sheet metal casing 11. A horizontal cylindrical boiler drum or shell 12 is mounted inside the furnace with one end projecting outwardly through a circular opening 14 in the wall 10. This opening is somewhat larger in diameter than the drum. The drum is supported by banks of water tubes 15 and 16 which are connected to other drums (not shown) to form a complete water tube boiler of well known construction. The end of the drum 12 is closed by a head 18 fastened to the cylindrical portion of the drum by rivets 19, as is common in the art.

It will now be understood that the tubes 15 and 16 will increase in length when heat is applied to them for the generation of steam, and this will cause the drum 12 to move in a direction perpendicular to its axis. The drum itself will also expand appreciably in an axial direction. The opening 14 is sufficiently large to permit these movements of the drum without interference with the wall 10, but it is necessary to provide some means to seal the opening around the drum and thus prevent leakage of air into the furnace.

The sealing means illustrated in the drawing comprises a ring 21 in the form of a flat annular plate surrounding the drum 12 and in contact with the outer surface of the wall casing 11. This

ring 21 has an outer diameter appreciably greater than the opening 14, and an inner diameter very slightly greater than the outside diameter of the drum. This slight clearance is preferably allowed between the ring and the drum, so that the latter may expand axially without tending to move the ring away from the wall.

I provide suitable means to hold the ring in close contact with the wall, and for this purpose I have shown a series of clamps 22 spaced about the periphery of the ring and each fastened to the wall casing 11 by a bolt 23. The heads of the bolts 23 are shown welded to the inside of the casing at 24 (Fig. 2) to hold them firmly in place. Each clamp 22 is shaped as a rectangular body having a bolt hole 26 therethrough and a rib 27 at one edge for contact with the wall. The bolts 23 are arranged in a circle substantially larger in diameter than the ring 21 so that they will not interfere with the sliding movement of the ring. These bolts are tightened only sufficiently to ensure contact between the ring and the casing 11, and the ring is free to slide in a vertical plane along the surface of the casing as the drum 12 moves relative to the furnace wall.

While the sealing ring 21 may be formed as a single unitary member, I prefer to construct this ring in sections for convenience in assembly. Three sections are shown in the illustrated embodiment, and they are fastened together by bolts 29 extending through outwardly extending ears or lugs 30 on the ring sections.

In order to prevent any air leakage through the slight clearance space between the ring 21 and the drum 12, I preferably provide a suitable flexible packing material such as asbestos rope 32 surrounding the drum outside the ring. This rope 32 is held in place by a cylindrical projecting shelf or sleeve 33 formed integral with the ring 21. This cylindrical portion 33 is larger in diameter than the drum, and the space between these parts is occupied by the asbestos packing.

A layer 35 of a suitable heat insulating material, such as 85% magnesia, is preferably placed against the outer surface of the drum head 18. This insulation is held in place by wires 36 fastened at their ends to the sleeve 33, holes 37 being provided therein for this purpose. A coating of a suitable finishing plaster 39 may be applied over the insulating layer. This plaster 39 is strengthened and reinforced by the wires 36, and not only provides a smooth finish for the drum head but also serves to hold the packing 32 in position within the sleeve 33.

The operation of the invention will now be apparent from the above disclosure. The drum 12 is free to move as a result of expansion or contraction of the tubes 15 and 16, and the sealing ring 21 will slide under the clamps 22, while at all times contacting with the wall casing 11 to prevent leakage of air into the furnace. The drum may expand freely in a lengthwise direction relative to the sealing ring, and leakage between these parts is prevented by the packing 32. This packing is permanently protected and held in place by the cylindrical portion 33. The wires 36 form a simple and effective means for supporting the insulation 35 on the drum head. This insulation is of a somewhat yielding nature so

that no substantial stress can be transmitted to the sealing ring by the wires. The entire construction is simple and inexpensive to manufacture and install, and yet it will positively prevent any material leakage of air into the furnace. There is nothing to get out of order, and the seal will remain tight throughout a long period without attention.

Having thus described my invention, what I claim as new and desire to secure by Letters Patent is,

1. The combination with a refractory furnace wall having an outer sheet metal casing, the wall and casing having a circular opening therethrough, a horizontal boiler drum smaller in diameter than the opening and extending through the opening, a sealing ring surrounding the drum outside the wall, the inner diameter of the sealing ring being slightly larger than the outer diameter of the drum, means to hold the sealing ring in sliding contact with the casing, an annular sleeve extending outwardly from the ring and spaced from the drum, and flexible packing means located in the space between the sleeve and the drum to prevent leakage of air between the drum and sealing ring.

2. The combination with a refractory furnace wall having an outer sheet metal casing, the wall and casing having a circular opening therethrough, a horizontal boiler drum smaller in diameter than the opening and extending through the opening, a sealing ring surrounding the drum outside the wall, the inner diameter of the sealing ring being slightly larger than the outer diameter of the drum, a series of spaced clamps bolted to the casing around the ring and serving to hold the ring in sliding contact with the casing, an annular sleeve extending outwardly from the ring and spaced from the drum, and flexible packing means located in the space between the sleeve and drum to prevent leakage of air between the drum and sealing ring.

3. The combination with a furnace wall having a circular opening therethrough, a horizontal boiler drum smaller in diameter than the opening and extending through the opening, a sealing ring surrounding the drum outside the wall, means to hold the sealing ring in sliding contact with the outside of the wall, an annular sleeve extending outwardly from the ring and spaced from the drum, flexible packing means located in the space between the sleeve and the drum, and plaster on the drum adjacent to the packing means to hold the packing means in place.

4. The combination with a furnace wall having a circular opening therethrough, a horizontal boiler drum smaller in diameter than the opening and extending through the opening, a sealing ring surrounding the drum outside the wall, means to hold the sealing ring in sliding contact with the outside of the wall, an annular sleeve extending outwardly from the ring and spaced from the drum, flexible packing means located in the space between the sleeve and the drum, plaster on the drum adjacent to the packing means to hold the packing means in place, and wires connected at their ends to the annular sleeve and arranged to reinforce the plaster.

MAX H. KUHNER.
